UNITED STATES PATENT OFFICE

153,101

DESIGN FOR A CHAIR

Alvin J. Bellin, Baltimore, Md., assignor to National Store Fixture Co., Inc., Baltimore,
Md., a corporation of Maryland

Application July 16, 1947, Serial No. 140,325

Term of patent 7 years

(Cl. D15—1)

To all whom it may concern:

Be it known that I, Alvin J. Bellin, a citizen of the United States, residing in the city of Baltimore, State of Maryland, have invented a new, original, and ornamental Design for Chair, of which the following is a specification, reference being had to the accompanying drawings, forming part thereof.

Fig. 2 is a view in perspective on a reduced scale showing the back of the chair.

Fig. 3 is a side elevation of the chair.

I claim:

The ornamental design for a chair, as shown.

ALVIN J. BELLIN.
